DISPLAY RACK FOR WINE AND CHAMPAGNE BOTTLES AND THE LIKE

Joseph N. Amigone, 3404 Main St., Buffalo, N.Y.

Continuation of design applications Ser. No. D. 66,039,
July 24, 1961, and Ser. No. D. 66,040, July 24, 1961.
This application Dec. 6, 1962, Ser. No. 72,805

Term of patent 14 years

(Cl. D80—10)

FIG. 2.

FIG. 3.

FIG. 4.

FIG. 5.

FIG. 6.

FIG. 7.

FIG. 1 is an elevational view taken from one side of a display rack for wine and champagne bottles and the like showing my new design, the opposite side being substantially the same as the side shown;

FIG. 2 is a top plan view thereof, the base being omitted for convenience of illustration;

FIG. 3 is a cross-sectional view thereof, taken on the line 3—3 of FIG. 1;

FIG. 4 is a perspective view thereof;

FIG. 5 is an elevational view taken from one side of a modified form of display rack for wine and champagne bottles and the like showing my new design, the opposite side being substantially the same as the side shown;

FIG. 6 is a top plan view of FIG. 5, the base being omitted for convenience of illustration; and

FIG. 7 is a cross-sectional view thereof, taken on the line 7—7 of FIG. 5.

The broken-line representations of bottles in FIGS. 1, 2, 3 and 5 are for purposes of illustration only.

This application is a continuation of my applications Serial Nos. D. 66,039 and D. 66,040, filed July 24, 1961, and now abandoned.

I claim:

The ornamental design for a display rack for wine and champagne bottles and the like, substantially as shown and described.
